UNITED STATES PATENT OFFICE

REUBEN B. BENJAMIN, OF CHICAGO, ILLINOIS, ASSIGNOR TO BENJAMIN ELECTRIC MFG. CO., OF DES PLAINES, ILLINOIS, A CORPORATION OF ILLINOIS

DESIGN FOR A LIGHTING FIXTURE

Application filed December 17, 1930. Serial No. 38,014. Term of patent 14 years.

To all whom it may concern:

Be it known that I, REUBEN B. BENJAMIN, a citizen of the United States, residing at Chicago, in the county of Cook and State of Illinois, have invented a new, original, and ornamental Design for a Lighting Fixture, of which the following is a specification, reference being had to the accompanying drawing, forming a part thereof, in which—

Fig. 2 is a side elevational view of the same; and

Fig. 3 is a top plan view of the same.

I claim:

The ornamental design for a lighting fixture substantially as shown.
